[57] **CLAIM**

The ornamental design for an electrical outlet protector, as shown and described.

DESCRIPTION

FIG. 1 is an environmental perspective view of an open electrical outlet protector showing my new design;
FIG. 2 is an environmental perspective view of a closed electrical outlet protector thereof;
FIG. 3 is a front elevational view thereof;
FIG. 4 is a left side elevational view thereof;
FIG. 5 is a right side elevation view thereof; and.
FIG. 6 is a top view, the bottom view being a mirror image thereof.
The undisclosed rear is plain and unornamented.
The broken line showing of an electrical receptacle in FIG. 1 is for illustrative purposes only and forms no part of the claimed design.
